UNITED STATES PATENT OFFICE.

CHARLES H. QUARLES, OF AKRON, OHIO.

PUZZLE.

1,133,061.

Specification of Letters Patent. Patented Mar. 23, 1915.

Application filed September 8, 1914. Serial No. 860,692.

To all whom it may concern:

Be it known that I, CHARLES H. QUARLES, a citizen of the United States, residing at Akron, in the county of Summit, State of Ohio, have invented certain new and useful 5 Improvements in Puzzles; and I do hereby declare the following to be a full, clear, and exact description of the invention, such as will enable others skilled in the art to which 10 it appertains to make and use the same.

This invention relates to puzzles.

The object of the invention resides in the provision of a puzzle, the solution of which will be interesting and amusing and at the 15 same time difficult.

With the above object in view, the invention consists in the details of construction, and in the arrangement and combination of parts to be hereinafter more fully described and particularly pointed out in the 20 appended claim.

In describing the invention in detail, reference will be had to the accompanying drawings wherein like characters of reference denote corresponding parts in the different views, and in which:

Figure 1 is a perspective view of a puzzle showing the parts in the position they would occupy during an initial step in the 30 solution; and Fig. 2, a view similar to Fig. 1 showing the position of the parts when the solution of the puzzle is complete.

Referring to the drawings, the improved puzzle is shown as comprising a body plate 35 10 which has slidably mounted therein for movement transversely thereof a plurality of rods or stems 11, 12, 13, 14, 15, 16, 17, 18, 19 and 20 and swiveled on corresponding ends of these stems are rings 11^a, 12^a, 13^a, 40 14^a, 15^a, 16^a, 17^a, 18^a, 19^a and 20^a respectively. The rings 12^a, 13^a, 14^a, 15^a, 17^a and 20^a embrace respectively the stems 11, 12, 13, 14, 15 and 19. The ring 16^a embraces the stems 17 and 18 and the ring 18^a embraces 45 the stem 19, while the rings 11^a and 19^a are free. The puzzle further embodies an elongated loop 21, the purpose of which will appear in the description of the solution of the puzzle.

50 The object of the puzzle is to get the loop 21 into embracing relation with a desired rod or stem. For instance, in order to get the loop 21 into embracing relation with the stem 16 the rings 11^a and 12^a are first 55 passed through the loop and the latter is then pushed through ring 12^a and ring 11^a

then taken out of the loop. The ring 13^a is pushed through the loop and ring 11^a passed through the loop again. Then take rings 11^a and 12^a out of the loop and push ring 14^a through the loop and the latter through said ring. Rings 11^a and 12^a are then pushed through the loop again and rings 11^a and 13^a taken out of the loop. The ring 11^a is then put through the loop and rings 11^a and 12^a taken out of the loop which will leave the loop embracing the stem 14. Ring 15^a is then pushed through the loop and the latter through said ring. Rings 11^a and 12^a are then pushed through the loop and ring 11^a then taken out of the loop by pushing the latter through ring 12^a when the ring 13^a is put on the loop in the same manner as previously mentioned. Ring 11^a is then pushed through the loop again and rings 11^a and 12^a taken out of the loop, after which ring 14^a is taken out of the loop. Rings 11^a and 12^a are then put through the loop after which rings 11^a and 13^a are taken off and ring 11^a put through the loop and rings 11^a and 12^a then taken out of the loop which leaves the loop on stem 15. Ring 17^a is then passed through the loop and the latter passed through said ring. Rings 11^a and 12^a are then passed through the loop and ring 11^a subsequently taken out. Ring 13^a is then put on the loop and ring 11^a passed through the loop again. Rings 11^a and 12^a are then taken out of the loop. Ring 14^a is put 90 on the loop and rings 11^a and 12^a passed through the loop. Ring 14^a is put on the loop and rings 11^a and 12^a passed through the loop, take ring 11^a off the loop, take ring 13^a off, put ring 11^a on and then take rings 11^a and 12^a off, take ring 15^a off, put rings 11^a and 12^a through loop, take ring 11^a off put ring 13^a on, put ring 11^a through loop and take rings 11^a and 12^a off, take ring 14^a off, put rings 11^a and 12^a through loop, 100 take rings 11^a off, take ring 13^a off, put ring 11^a through loop, take rings 11^a and 12^a off, which leaves loop on stem 17.

To put the loop on stem 16 push the loop through ring 16^a and put the previous five 105 rings on the loop by pushing rings 11^a and 12^a through the loop and taking rings 11^a out and putting ring 13^a on and so on as has been previously referred to. Take the first four rings off the loop by pushing rings 11^a 110 and 12^a out of the loop and then take ring 14^a out. Pass rings 11^a and 12^a through the

loop, take 11^a out of the loop, take 13^a out, push 11^a through the loop again, take 11^a and 12^a out of the loop which will leave the loop on stems 15 and 17. Ring 17^a is then 5 put through loop and kept above the latter. The first four rings are then put on the loop and the first three rings taken off by pushing ring 11^a out of the loop and ring 13^a out and so on which will leave the loop 10 on stem 14. Push ring 15^a through the loop the same as ring 17^a. Put the first three rings on and then take 11^a and 12^a off push ring 14^a through the loop the same as 17^a and 15^a, pass 11^a and 12^a through the loop 15 take 11^a out of the loop, push ring 13^a through the loop the same as 17^a and 15^a, pass 11^a through the loop. Reverse the puzzle and work rings 16^a, 18^a, and 19^a above the loop. Push the loop through 20 the ring 20^a and then push rings 19^a and 18^a through the loop. Take ring 19^a out of the

loop, put ring 16^a through the loop and keeping it above the loop put the ring 19^a through the loop. Then push all the rings through the loop by permitting the latter 25 to turn in ring 20^a and it will leave the loop on stem 16.

What is claimed is:

A puzzle comprising a body plate, a plurality of stems slidably engaged through 30 said plate, rings swiveled on corresponding ends of said stems respectively, certain of said rings embracing certain of said stems and the remainder of said rings being free, and an elongated loop engageable through 35 the rings.

In testimony whereof, I affix my signature, in the presence of two witnesses.

CHARLES H. QUARLES.

Witnesses:

JESSE SHIELDS,
Jos. L. BOWLER.
